UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAYBOLT STRUCTURE.

1,393,351.

Specification of Letters Patent. Patented Oct. 11, 1921.

Application filed January 20, 1920. Serial No. 352,695.

To all whom it may concern:

Be it known that I, ETHAN I. DODDS, a citizen of the United States, and a resident of Pittsburgh, in the county of Allegheny 5 and State of Pennsylvania, have invented certain new and useful Improvements in Staybolt Structures; and I do hereby declare the following to be a full, clear, and exact description of the invention, such as 10 will enable others skilled in the art to which it appertains to make and use the same.

This invention relates to improvements in staybolt structures for boilers, and more particularly to means for mounting the headed end of a staybolt and connecting the same with the outer boiler sheet,—the object of the invention being to provide a mounting which will constitute a bearing member and 15 a closure, and which may be mounted in the boiler sheet in any one of several ways.

With this and other objects in view, the invention consists in certain novel features of construction and combinations of parts 20 as hereinafter set forth and pointed out in the claims.

In the accompanying drawings; Figure 1 is a sectional view, partly in elevation, showing an embodiment of my invention, 25 and illustrating one way in which the same may be mounted, Figs. 2 and 3 are views showing other ways in which the device may be mounted in and connected with the boiler sheet, and Figs. 4, 5, 6 and 7 are views of 30 modifications.

1 represents an outer boiler sheet and 2 the inner sheet of a boiler. In Fig. 1 the outer boiler sheet is shown provided with 35 an opening 3, a portion of the wall of which 40 is rounded to form a seat 4, and another portion of said wall may be beveled as at 4^a.

My improved bearing member and closure 45 5 may be constructed in a single piece and is made hollow for the reception of the head 6 at the outer end of a staybolt 7, the inner 50 end of the latter being secured to the inner boiler sheet 2 in any suitable manner. After 55 the head of the bolt shall have been inserted into the bearing member, the open end of 50 the latter will be forged under said head so 60 as to permanently inclose the latter,—the forging operation being such that a rounded 65 interior seat 8 will be provided for the head 70 of the staybolt and formed with a rounded 75

exterior portion 8^a which may be mounted 55 in the boiler sheet as hereinafter described.

The interior of the member 5 has such configuration and proportions as to provide 60 a clearance space 6^a for the bolt head.

The bearing member 5 is formed with an 65 enlarged outer end or head portion 9 having an angular recess 10 to receive a wrench and the peripheral portion of the part 9 is rounded, as at 11 so that the bearing member may 70 have a universally movable or adjustable mounting on the seat 4 in the opening in the outer boiler sheet, whereby said bearing may be so adjusted as to insure proper alignment of the staybolt with its points of connection with the respective boiler sheets. When properly adjusted or positioned, the bearing member will be welded to the outer boiler sheet by a weld 12, the latter occupying 75 a groove formed by the beveled portion 4^a of the wall of the opening in the boiler sheet and a beveled edge portion 13 of the enlarged or headed end 9 of the bearing member.

Between the enlarged or headed outer end 80 portion 9 and the rounded inner end portion 8^a of the bearing member, the latter is threaded externally as at 14.

It will be observed that in Fig. 4, the outer end of the bearing member is substantially 85 flush with the outer face of the outer boiler sheet, but the said member is so constructed that it may have threaded connection with the boiler sheet and project outwardly beyond the latter.

In Fig. 2, the opening in the boiler sheet 90 has a threaded wall 15 to be engaged by the threaded portion 14 of the bearing member. Thus the device is adapted for use in an opening in the boiler sheet from which an 95 old threaded sleeve or bushing has been removed. When the device is mounted as shown in Fig. 2, the enlarged or headed end 9 may overlie the boiler sheet, and a gasket 16 may be countersunk into the boiler sheet 100 around the opening therein and under the head 9 and the inner edge of this gasket may project inwardly over a portion of the opening in the boiler sheet. The enlarged or headed end 9 of the device may be welded 105 to the boiler sheet as indicated at 17.

If desired, the bearing device may be mounted as shown in Fig. 3, wherein said device has a universally movable or adjust-

able mounting at its rounded inner end portion 8^a in the opening in the boiler sheet, the wall of said opening being made with a rounded seat 18 to receive said rounded portion 8^a. The bearing member will be united to the boiler sheet by a weld 19 surrounding a part of the threaded portion 14 of the device.

It will be observed that my improved bearing device also constitutes a closure over the bolt head and for the opening in the boiler sheet.

In the embodiment of the invention shown in Figs. 4, 5 and 6, 1^a represents an outer boiler sheet and 2^a the inner sheet of a boiler. In Fig. 4, the outer boiler sheet is shown provided with an opening 3^a, a portion of the wall of which is rounded to form a seat 4^b and another portion of said wall may be beveled, as at 4^b.

The bearing member 5^a may be constructed in a single piece open at both ends,—its inner end portion being rounded exteriorly as at 6^b to be mounted on the rounded wall of the opening in the boiler sheet as hereinafter explained.

The rounded inner end portion 6^b of the bearing member provides an interior rounded seat 7^a for the head 8^b of a staybolt 9^a,—the inner end of the latter being secured to the inner boiler sheet in any suitable manner.

The bearing member 5^a is enlarged to form an annular head 10^a having a rounded peripheral face 11^a to have a universally movable or adjustable mounting upon the seat 4^b in the boiler sheet, whereby the bearing member may be so adjusted as to insure proper alignment of the staybolt with its points of connection with the respective boiler sheets. When properly adjusted, the bearing member will be welded to the boiler sheet by a weld 12^a, the latter occupying a groove formed by the beveled portion 4^b of the wall of the opening in the boiler sheet and a beveled portion 13^a of the annular head 10^a.

The interior of the annular head 10^a of the bearing member 5^a is threaded and receives an exteriorly threaded removable plug closure 14^a, the latter lying flush with the outer end of the head of the bearing member and with the outer face of the outer boiler sheet, and said plug closure may be made with an angular recess 15^a to receive a wrench.

The bearing member is made intermediate of its ends, with an externally threaded portion 16^a so that said bearing member may be mounted in an opening 17^a in the boiler sheet, having a threaded wall, as shown in Fig. 5, in which case, the annular head of said bearing member may overlie the boiler sheet and be welded to the latter, as shown at 18^a.

In Fig. 6, the inner rounded end portion of the bearing member is shown as having a universally adjustable mounting in the opening in the boiler sheet, and the threaded portion 16^a of said bearing member welded to the outer boiler sheet, as at 19^a.

In the embodiment of the invention shown in Fig. 7, 1^b represents an inner boiler sheet with which the inner end of a staybolt 2^b is connected in any suitable manner and said staybolt is provided at its outer end with a rounded head 3^b and this head is connected with the outer boiler sheet 4^c by means of devices which will be hereinafter described.

The outer boiler sheet 4^c is provided with an opening 5^b, a portion of the wall of which is threaded as at 6^c. A hollow bearing and closure member 7^b enters the opening in the boiler sheet and is made with an exterior threaded portion 8^c to mesh with the threads 6^c in the wall of said opening. The inner end portion 9^b of the member 7^b is rounded and in order that this rounded end portion may be made to inclose the head 3^b of the staybolt and afford a bearing 11^b for said head, the blank from which said member 7^b is made may be slotted as at 10^b and said inner end of the member 7^b pressed into the position shown in the drawing by forging.

It will be observed that the interior contour and dimensions of the member 7^b are such as to provide a clearance space 12^b for the head of the staybolt.

The member 7^b is provided with an angular head 13^b to receive a wrench and it is also provided with an annular flange 14^b which overlies the outer face of the boiler sheet and between said annular flange and the boiler sheet a gasket 15^b is located,—said gasket being preferably disposed in an annular groove or recess in the outer face of the boiler sheet around the opening in the latter.

The inner end portion of the opening in the boiler sheet may be rounded and has such dimensions as to afford a clearance space 16^b between the rounded inner end portion of the member 7^b and the adjacent wall of the opening 5^b.

Having fully described my invention what I claim as new and desire to secure by Letters-Patent, is:—

1. In a staybolt structure, a bearing member having an internal seat for the head of a staybolt, said bearing member having an annular unthreaded outer end portion and having its inner end portion rounded lengthwise of the member, said bearing member also having an exterior threaded portion between said annular unthreaded outer end portion and the said rounded portion.

2. A bearing device for the head of a staybolt, having an interior seat for the head

of a staybolt, an exterior rounded inner end portion, said bearing device provided with an exteriorly rounded outer end portion and an exterior threaded portion between said 5 outer and inner end rounded portions.

3. The combination with a boiler sheet having an opening, of a hollow bearing member, one end of which is closed and a staybolt provided with a head having a seat 10 in said bearing member, said bearing member having a rounded exterior inner end portion and provided with an unthreaded outer end part having a rounded portion to engage the boiler sheet, and said bearing 15 member also having an exterior threaded portion between its outer and inner end rounded portions, and a weld securing said bearing member to the boiler sheet.

4. In a staybolt structure, the combination 20 with a boiler sheet having an opening, of a bearing member having a part at its outer end to provide a seat for said bearing member on the boiler sheet, said bearing member having an exteriorly rounded inner end portion 25 and an exteriorly threaded portion between the outer end portion and the rounded inner end portion, and a staybolt having a head mounted in said bearing member.

5. The combination of a hollow bearing 30 member and a staybolt having a head per-

manently inclosed in said bearing member, said bearing member having such internal configuration as to afford clearance space for the bolt head, and said bearing member having integral rounded portions near respective ends to be mounted in a boiler sheet and also having an intermediate threaded portion to engage the threaded wall of an opening in a boiler sheet. 35

6. In a staybolt structure, the combination 40 with a boiler sheet having an opening, of a bearing member to enter said opening and provide a closure, said bearing member being hollow, a staybolt having a head permanently inclosed in said bearing member and 45 having such configuration relatively to that of the interior of the bearing member that a clearance space will be provided in the latter for the bolt head, said bearing member having an exteriorly rounded inner end portion and an enlarged or headed outer end portion having a rounded peripheral portion, and said bearing member having a threaded portion between said rounded portions, and a weld uniting said bearing member to the boiler sheet. 50 55

In testimony whereof, I have signed this specification.

ETHAN I. DODDS.
